UNITED STATES PATENT OFFICE

RAYMOND L. JOHNSON, OF CHICAGO, ILLINOIS

PATTERN MAKER'S DOWEL

Application filed April 25, 1930. Serial No. 447,811.

This invention relates to certain novel improvements in pattern maker's dowels.

One of the objects of my invention is to provide a pattern maker's dowel, the male and female parts of which are interchangeable.

Another object of my invention is to provide a pattern maker's dowel, the cope and drag portions of which can be quickly driven 10 into the cope and drag holes in wooden forms by means of a hammer or other like object.

Another object of my invention is to provide a pattern maker's dowel, the cope and drag parts of which may be allowed to remain 15 permanently in the wooden cope and drag form.

Still another object of my invention is to provide a pattern maker's dowel having a pin which is interchangeable between the 20 cope and drag parts of the dowel and which may be quickly removed from either cope or drag by means of a nail or similar object and likewise inserted in the cope or drag by means of a nail or like object.

25 Other objects will appear hereinafter.

The invention consists in the novel combination and arrangement of parts to be hereinafter described and claimed.

The invention will be best understood by 30 reference to the accompanying drawing, showing the preferred form of construction and in which:

Fig. 1 shows a pattern maker's wooden form in open position with the parts of my 35 dowel inserted in position in cope and drag;

Fig. 2 is a sectional view showing a pattern maker's wooden form in closed position with my dowel therein in closed position; and

40 Fig. 3 is a view taken substantially on the line 3—3 on Fig. 2 showing a cross section of my dowel with the interchangeable pin removed, illustrating the manner of securing the dowel in fixed position in either the cope or drag part of the wooden form.

Referring to the drawing wherein I have 45 illustrated the preferred form of construction for my invention, 1 indicates the drag portion of a pattern maker's wooden form 50 and 2 indicates the cope portion thereof. In-

serted in the cope portion 2 is one of the two exactly similar parts 3 of my dowel with the interchangeable pin 4 in the cope thus constituting the male half of the dowel 3b as used in working position. One dowel 55 is shown at each end of the cope and drag of the pattern better to illustrate the manner of use. In the particular structure shown in the drawing there is inserted in the drag portion 1 of the wooden pattern the female 60 structure 3a of the dowel and the male structure is inserted in the cope of the wooden pattern. As will be explained hereinafter, however, my dowel comprises two exactly similar parts so that the distinction between the 65 male and female parts thereof does not exist except when the interchangeable pin 4 is screwed into one of the two similar parts to constitute that part the male member of the dowel. Hereinafter, therefore, the similar cope and drag structures will be generically referred to as 3, whereas, for purpose of distinction and clearness, I will designate the male structure of the dowel as 3b when the same is in working position. Likewise, 70 hereinafter I will refer to the female part of the dowel as 3a, it being understood that the interchangeable pin 4 of the dowel is then in the cope portion of the dowel to constitute the same the male half thereof 3b. 75

In the construction of my invention the cope and drag structures 3 are machined from brass or other like material to form a substantially cylindrical housing 5 as best illustrated in Fig. 3. Hereinafter it is understood that when I refer to 5 I mean to designate thereby the cylindrical housing as the basic structure to which to refer for describing the other features of the pin housing that are integral therewith and to be described 80 85 hereinafter.

At one end of the substantially cylindrical housing structure 5 and integral therewith is a substantially disc-shaped flange 6 extending circumferentially around the cylinder 5. The outer surface of the disc-shaped flange structure 6 is flat so that when the male and female parts of the dowel rest adjacent each other in working position a perfect union 90 will be formed. Extending longitudinally 95 100

of the middle portion of the cylindrical housing 5, on the exterior surface thereof, and integral therewith, are substantially triangularly-shaped ridges or ribs 8 as best shown in Fig. 3.

5 The cylindrical housings 5 are bored internally throughout their entire length along the longitudinal axis of the housing to provide sockets and these sockets are constricted in diameter at the bottom portions thereof as 10 shown in Fig. 2. The constricted lower portions of the sockets are screw threaded as shown at 7 in Fig. 2.

The interchangeable pin 4 is cylindrical in shape throughout its main body portion.

15 The pin 4 is constricted in diameter at one end thereof and this constricted portion is screw-threaded so that the pin may be readily inserted into the screw-threaded constricted portions of the sockets as best shown in Fig. 2.

20 When in this position interiorly of the housing 5, the housing 5 and the pin 4 constitute the male structure of the dowel. As explained hereinbefore the pin 4 may be exchanged between the housings 5 so as to constitute either one of the housings the male structure of the dowel, the other remaining the female structure thereof. The pin 4 is tapered conically at the end opposite the 25 screw threaded portion as best illustrated in Fig. 2 and this tapered portion has a hole 10 extending therethrough transversely of the longitudinal axis of the pin.

30 In the use of my dowel the female structure 35 3a thereof is driven into the drag portion of the pattern maker's form and the male structure is driven into the cope portion of the pattern maker's form in suitably shaped holes drilled therefor in a manner well known 40 in the art. In case the pattern maker should mistakenly drive the male structure of my dowel into the drag portion of the wooden form he may easily and quickly unscrew the pin 4 from the drag by means of a finishing 45 nail or similar object, and likewise quickly and conveniently screw the pin into its proper position in the cope.

50 In case the pattern maker discovers after he has inserted the male and female structures 55 of my dowel into position in cope and drag respectively that he wishes to change the position of the male and female structures of the dowel in cope or drag, so as to place the male and female parts of the dowel in a stronger 60 and more suitable portion of the cope and drag of the pattern, or should he wish to plane the surface wherein he has inserted the male and female parts of the dowel, he may quickly and conveniently remove the male 65 part of the dowel by inserting a nail through the hole in the pin and exerting pressure thereon which will readily pry the male part of the dowel out of position in the cope of the pattern. Likewise, the female part of the 70 dowel may be removed in a similar manner

by inserting the pin therein. Should the pattern maker have occasion to discard the wooden pattern he may quickly and conveniently remove the parts of the dowel therefrom and thus salvage the dowel for further use.

70 When driven into suitable holes in the cope and drag of the pattern the housings are held rigidly therein by means of the substantially triangularly-shaped ridges 8 which engage the fibers of the wood and prevent movement 75 of the male and female parts of the dowel therein. When the male and female parts of the dowel are driven into suitable holes in the cope and drag of the pattern the triangularly-shaped ridges 8 on the housings 5 engage the fibers of the wood tending to displace the fibers outwardly therefrom so that the spring like resistance of the fibers creates pressure against the wall of the housing; and when the disc-shaped flange 6 engages these 80 outwardly bent fibers it has a tendency to compress them against the wall of the housing between the upper extremities of the ridges 8 and the lower edge of the flange 6 so that the fibers are held rigidly against the 85 wall of the housing. The housing is, in this manner, held securely in the hole drilled therefor in the wood and accidental removal is prevented because the ridges 8 will, when 90 the dowel is turned into inverted position, engage the fibers compressed in the space between the upper ends of the ridges and the lower edge of the flange and thus prevent accidental escape of the male and female parts 95 of the dowel.

100 It is apparent from the foregoing description of my invention that I have described a dowel which is efficient in use, has a pin which is interchangeable between the cope and drag of a pattern, which can be quickly and easily 105 driven into the wooden cope and drag pattern used in pattern making, and which eliminates the necessity of unscrewing or removing the male and female structures of the dowel from the holes drilled therefor in the wooden cope 110 and drag forms of the pattern and reinserting them in proper position in case the pattern maker makes a mistake in positioning the male and female structures of the dowel in 115 unsuitable position in either cope or drag, or inserts the male structure of the dowel in the drag and the female structure in the cope whereas the proper position is the converse thereof.

120 While I have illustrated and described the preferred form of construction for carrying my invention into effect, this is capable of variation and modification, without departing from the spirit of the invention. I, therefore, do not wish to be limited to the precise 125 details of construction set forth, but desire to avail myself of such variations and modifications as come within the scope of the appended claims.

130 Having thus described my invention what

I claim as new and desire to protect by Letters Patent is:

- 5 1. A dowel pin structure comprising a pair of axially opposed members each provided with a socket threaded in part, a pin including a head and a threaded shank interchangeably receivable in the threaded part of one socket with said head extending into the unthreaded part of the other socket, said head having a tool-receiving slot extending transversely therethrough for inserting said pin into and removing it from its socket, and ribs 10 on the exterior of said members adapted to engage the walls of a recess to secure said members therein.
- 15 2. A dowel pin structure comprising a pair of axially opposed members each having formed therein a socket, each of said sockets having a threaded portion and an unthreaded portion, and a pin having a threaded shank interchangeably threadable into said threaded portions of said sockets, said pin including a head interchangeably receivable in said unthreaded portions of said sockets and said head having a tool-receiving slot extending 20 transversely therethrough.
- 25

In testimony whereof I affix my signature.
RAYMOND L. JOHNSON.
